UNITED STATES PATENT OFFICE

CHARLES W. EDWARDS, OF WASHINGTON, DISTRICT OF COLUMBIA

WALNUT, ETC., PIERCING MACHINE

Application filed September 26, 1929. Serial No. 395,325.

My invention relates to piercing machines and an object of the same is to provide a continuously operated mechanism wherein nuts or other objects will be singly delivered to a reciprocable piercing element.

A further object of the invention is to provide a machine of this character embodying a reciprocatory piercing element and a rotatable feeding device which is rotated step by step to singly bring the nuts or other objects into the path of the reciprocating piercing element.

The invention also contemplates a machine of this character whereby large quantities of nuts or other objects will be expeditiously pierced preparatory to placing the same in a preservative.

With the preceding and other objects and advantages in mind, the invention consists in the novel combination of elements, constructions and arrangements of parts and operations to be hereinafter more fully described, claimed and illustrated in the accompanying drawings, wherein:

Figure 1 is a side elevation of the machine;

Fig. 2 is a rear elevation of the same;

Fig. 3 is a perspective of the hopper embodied in the invention;

Fig. 4 is a fragmentary vertical section taken on line 4-4 of Fig. 1;

Fig. 5 is an enlarged detail view having parts broken away;

Fig. 6 is a top plan view of the machine;

Fig. 7 is a fragmentary sectional view of parts of the machine; and

Fig. 8 is a transverse section taken on substantially the line 8-8 of Fig. 6.

Referring to the invention in detail a base 5 is provided from which pairs of vertical posts or uprights 6 arise.

A horizontal table or shelf 7 is mounted on the upper ends of the legs 6 and as disclosed in Fig. 6 is provided with a central opening or cut out portion 8. Arising from the base and extending through the central opening at the rear end thereof is a pair of parallel standards 9. Secured to the outer face of each of the standards 9 is a tubular guide 10 in each of which a plunger 11 is mounted for reciprocatory movement in a

vertical direction. An angle plate 12 is attached to the lower end of each of the plungers and cast therewith is a horizontally extending plate 13. Depending from each of the plates 13 is a row of longitudinally aligned tines or piercing elements 14 adapted to pass through perforated clearing plates 15 mounted below the plungers 11, the clearing plates having right angular attaching flanges 16 which are secured to the standards as at 17. A wear plate 18 is attached to each of the standards below the guides 10 to prevent wear incident to the movement of the plungers 11 and associated parts.

For the purpose of reciprocating the plungers a horizontally disposed drive shaft 19 is journaled upon the upper ends of the standards and attached to the ends thereof are crank arms 20 with which pitman rods 21 are connected. The pitman rods 21 extend parallel to the standards 9 and are pivotally connected with the upper ends of the plungers as at 22.

A main power shaft 23 is supported in the standards 9 below the table and rotatable therewith is a pulley 24 provided with a sprocket wheel 25 at one end. A sprocket chain 26 passes around this sprocket wheel and extends upwardly between the standards and is trained about a larger sprocket wheel 27 fixed to the shaft 19.

Power is supplied to the power shaft 23 from a motor 28 mounted on the base 5. A drive belt 29 passes around the pulley 24 and a smaller pulley 30 fixed to the motor shaft.

For the purpose of singly delivering a nut or other object into the path of each set of tines 15 a revoluble circular carrier 31 is mounted upon the table 7 adjacent each of the clearing plates 15. As disclosed particularly in Fig. 6 each carrier is formed with a plurality of radially disposed pockets or recesses 32 in the periphery, which are of such size as to receive a nut or other spherical object. Blocks 31a are secured to the table to one side of each of the carriers and are provided with semi-circular inner faces 32a embracing the carriers. For each carrier 31 a drive shaft 33 is provided. The drive shafts extend vertically through the table and are

fixed to the carriers. A bevelled gear 34 is fixed to the lower end of each of the shafts 33 and is engaged by bevelled gears 35 fixed to shafts 36, the latter being journaled in the 5 standards 9.

In order to rotate the carriers step by step to successively bring the pockets 32 in vertical alinement with the tines 14 a ratchet wheel 37 is fixed to the inner end of each of the 10 shafts 36. An arm 38 is pivotally mounted on the inner end of each of these shafts 36 and carries a spring pressed pawl 39 which engages the ratchet wheel. For each of the 15 arms 38 a vertically extending actuating rod 40 is provided and has its lower end pivoted to the outer end of one of the arms 38 and its upper end pivotally connected with a lever 41, the levers 41 being pivotally supported from angularly extending arms 42 fixed to the upper 20 ends of the standards 9. Rotatable with the shaft 19 in vertical alignment with the levers 41 are arms 42 carrying rollers 43 at their outer ends which are adapted to engage the levers 41 to lift the same. It will be observed that upon each revolution of the arms 25 42 the levers 41 will be lifted and in turn raise the arms 43 to engage the pawls 39 with their respective ratchet wheels and rotate the same a predetermined distance. In turn the carriers 31 are rotated through the instrumentality of the shafts 33 to cause their pockets to successively register with the tines 14.

In order to normally hold the carriers stationary a spring pressed plunger 45 is mounted in a casing 46 at one side of each carrier. A disk 47 is secured to the under face of each carrier and is provided with notches 48 which register with pockets 32. A series of notches 49 is provided in each disk and are adapted 40 to successively engage one of the plungers 45.

The nuts or other objects are fed to the carriers from a rectangular tray or hopper 50 which extends entirely across the rear end of the table 7. The hopper is provided with an 45 inverted V-shaped bottom 51 which is inclined toward the front wall of the hopper to cause the objects to feed through outlet openings 52 and roll onto the plate 7. The rear and side walls of the hopper overlap the rear 50 and side edges of the table to retain the hopper thereon. In the operation of the invention the nuts or other objects rolling on to the table 7 are individually received in the pockets of the rotating carriers. In this connection it is pointed out that the pockets and outlet 55 openings 52 are so positioned relative to each other that each nut rolling from the hopper is confined in one of the pockets. Continued rotation of the carriers successively 60 brings the nuts below the reciprocating plungers. At this time the descending plunger causes the tines to penetrate the nuts. As the carriers rotate the pierced nuts are discharged through openings 53 provided in the 65 table at points diametrically opposite the

tines 14. In actual practice suitable receptacles will be positioned below the openings 53 to receive the pierced nuts falling therethrough.

I claim:

In combination a base, a reciprocatory piercing element mounted above the same, a perforated clearing plate supported below the piercing element, a shaft supported above the piercing element and having operative connection therewith, a carrier supported below the clearing plate, a shaft operatively connected with the carrier, a pawl and ratchet mechanism associated with the shaft, and means for actuating the pawl and ratchet mechanism embodying a lever mounted above the first mentioned shaft, a longitudinally movable vertically extending rod connected with the lever and one part of the pawl and ratchet mechanism, and an arm fixed to the shaft and disposed in the path of movement of the lever to raise the same at predetermined intervals.

CHARLES W. EDWARDS.
